HANDLE FOR SPOONS, &c.

No. 20,466.

20,466. HANDLE FOR SPOONS, &c. —Charles Osborne, New York, N. Y., assignor to The Whiting Manufacturing Company, same place. Application filed December 2, 1890. Serial No. 373,371. Term of patent 3½ years.

Patented Jan. 6, 1891

UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A HANDLE FOR SPOONS, &c.

SPECIFICATION forming part of Design No. 20,466, dated January 6, 1891.

Application filed December 2, 1890. Serial No. 373,371. Term of patent 3½ years.

To all whom it may concern:

Be it known that I, CHARLES OSBORNE, of the city, county, and State of New York, have invented a new and original Design for a Handle for Flat Ware, of which the following is a full, clear, and exact description, reference being had to the accompanying photograph, which represents a front and reverse view of a spoon-handle, showing my design, the handle being attached to the spoon-bowl in the ordinary way, and these two views being deemed necessary to fully illustrate my design.

The leading feature of my design consists in producing in relief upon both edges of the handle a series of **C** and **S** scrolls.

A is the spoon-bowl, and **B** the handle, the central part of which handle from the bowl to the top is smooth, and the handle terminates at the top in the petal-like figures **C**, the **C**-shaped scrolls **D** being produced alternately with their concave and convex sides

outward, and the **S**-scrolls **E** are produced on the edges of the handle at intervals between the **C**-scrolls, the **S**-scrolls **E** having centrally thereon flower-like figures which are produced in relief, and the scroll-like figures **D** and **E** are reduced in size through the shank of the handle, and at the point where the handle joins the bowl the scroll-like figures **E'** are produced, said figures being made to die away in the edges of the spoon-bowl.

The **C** scrolls **D** have flower-like figures produced centrally in relief upon their concave sides, and the effect of the scroll-like figures **D** and **E** is that of an irregular molding produced around the edge of the handle.

I claim—

The design for a handle for flat ware herein shown.

CHARLES OSBORNE.
